(No Model.)

H. SOHMER.

AGRAFFE BAR FOR PIANOS.

No. 268,562.

Patented Dec. 5, 1882.

UNITED STATES PATENT OFFICE.

HUGO SOHMER, OF NEW YORK, N. Y.

AGRAFFE-BAR FOR PIANOS.

SPECIFICATION forming part of Letters Patent No. 268,562, dated December 5, 1882.

Application filed June 1, 1882. (No model.)

To all whom it may concern:

Be it known that I, HUGO SOHMER, of the city, county, and State of New York, have invented certain new and useful Improvements 5 in Agraffe-Bars for Square and Grand Pianos, of which the following is a specification.

This invention has reference to an improved agraffe-bar for the upper three octaves or treble of square and grand pianos, whereby the quality of the tone in the treble is considerably improved, and made clear and pure; and the invention consists of a wedge-shaped agraffe-bar, which is set into a corresponding recess or recesses of an upright bar, cast integral with the 15 supporting-plate, secured to the wrest-plank. The agraffe-bar is provided with inclined perforations, through which the strings are passed.

In the accompanying drawings, Figure 1 represents a perspective view of my improved 20 agraffe-bar, shown in vertical transverse section through the end thereof; and Fig. 2 is a detail perspective view of the agraffe-bar detached from the supporting-plate.

Similar letters of reference indicate corresponding parts.

Referring to the drawings, A represents the 25 wrest-plank of a square or grand piano, and B a supporting-plate which extends over the upper three octaves or treble, and which plate 30 is provided with an upright bar, C, that is cast integral therewith and strengthened by a number of bracket-shaped pieces, C', as shown clearly in Fig. 1. The vertical bar C is provided at its base or connection with the supporting-plate

B, with a tapering recess or recesses, a, which 35 are arranged intermediately between the stiffening-brackets C', the recesses serving as the retaining sockets or bearings for the treble agraffe bar or bars D, which are made of brass and of wedge shape, so as to fit exactly into 40 the recesses of the bar C. The agraffe-bar D is provided with inclined perforations d, arranged in groups of three, for the strings of each note of the treble, which receive thereby a solid and perfect bearing. The consequence is an improved 45 quality and clear ring of tone in the treble, which is a desideratum, as the treble forms generally the weakest part of pianos.

Having thus described my invention, I claim as new and desire to secure by Letters Patent— 50

As an improvement in agraffe-bars for square and grand pianos, the combination, with a supporting-plate, B, having an upright bar, C, said bar being cast integral with plate B, and provided with a recess or recesses having inclined 55 sides, of a wedge-shaped agraffe bar or bars, D, secured into the recess or recesses of the upright bar, and provided with groups of inclined perforations for the strings, substantially as set forth.

In testimony that I claim the foregoing as my invention I have signed my name in presence of two subscribing witnesses.

HUGO SOHMER.

Witnesses:

M. PARPART,
GEORGE REICHMANN.
